FIG. 1 is a perspective view of a handle in accordance with an embodiment of my invention;

FIG. 2 is a top view of the embodiment shown in FIG. 1;

FIG. 3 is a front view of the embodiment shown in the previous figures;

FIG. 4 is a right side view of the embodiment shown in the previous figures;

FIG. 5 is a rear view of the embodiment shown in the previous figures; and

FIG. 6 is a sectional view taken as indicated by the lines and arrows 6—6 in FIG. 3.

The shading employed does not connote actual appearance, but is an expedient to best illustrate the shape of the handle.

I claim:

The ornamental design for a handle, as shown and described.
